US0D1036935S

(12) **United States Design Patent** (10) Patent No.: **US D1,036,935 S**
(45) Date of Patent: ** *Jul. 30, 2024

(54) **TUMBLER**

(71) Applicant: **YETI Coolers, LLC**, Austin, TX (US)

(72) Inventors: **Dustin Bullock**, Austin, TX (US);
Colin Darling, Austin, TX (US); **Liza Morris**, Austin, TX (US); **Mark Carlson Rane**, Austin, TX (US)

(73) Assignee: **YETI Coolers, LLC**, Austin, TX (US)

(*) Notice: This patent is subject to a terminal disclaimer.

(**) Term: **15 Years**

(21) Appl. No.: **29/776,770**

(22) Filed: **Mar. 31, 2021**

Related U.S. Application Data

(63) Continuation of application No. 29/658,676, filed on Aug. 1, 2018, now Pat. No. Des. 917,970.

CLAIM

The ornamental design for a tumbler, as shown and described.

DESCRIPTION

FIG. 1 is a top, front perspective view of a tumbler showing our new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines depicting the remainder of the tumbler form no part of the claimed design.
